(57) **CLAIM**

The ornamental design for a digital microscope as shown and described.

DESCRIPTION

FIG. 1 is a front perspective view of a digital microscope, showing my new design;

FIG. 2 is a rear perspective view thereof;

FIG. 3 is a rear perspective view of the digital microscope in another angle;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof;

FIG. 10 is a partial enlarged view of FIG. 1;

FIG. 11 is a partial enlarged view of FIG. 1;

FIG. 12 is a partial enlarged view of FIG. 4;

FIG. 13 is a partial enlarged view of FIG. 7;

FIG. 14 is a partial enlarged view of FIG. 7; and,

FIG. 15 is a front perspective view of the digital microscope in a detached state.

The dash-dash broken lines in the figures are for the purposes of illustrating portions of the digital microscope and form no part of the claimed design.

The dash-dot-dot lines in FIG. 15 are for the purposes of illustrating boundaries of the claimed design and form no part thereof.

The dash-dot-dash lines in the drawings are for annotating the enlarged views and form no part of the claimed design.
